DESIGN FOR A PIN OR SIMILAR ARTICLE

Fred E. Gross, Lonoke, Ark.

Application January 16, 1942, Serial No. 105,243

Term of patent 3½ years

To all whom it may concern:

Be it known that I, Fred E. Gross, a citizen of the United States, residing at Lonoke, in the county of Lonoke and State of Arkansas, have invented a new, original, and ornamental Design for a Pin or Similar Article, of which the following is a specification, reference being had to the accompanying drawing, forming part thereof.

I claim:

The ornamental Design for a pin or similar article, as shown.

FRED E. GROSS.
